UNITED STATES PATENT OFFICE.

WILLIAM BARBER, OF NEW YORK, N. Y., ASSIGNOR TO ADA S. BARBER, OF BROOKLYN,
NEW YORK.

COUPLING MECHANISM.

1,324,777.

Specification of Letters Patent. Patented Dec. 16, 1919.

Application filed August 16, 1916. Serial No. 115,243.

To all whom it may concern:

Be it known that I, WILLIAM BARBER, a citizen of the United States, residing at New York, in the county of Kings, State of New York, have made a certain, new and useful Invention in Coupling Mechanism, of which the following is a specification.

This invention relates to coupling mechanism.

10 The object of the invention is to provide a coupling mechanism for coupling tractors and trailers, cars or the like, which is simple in structure, efficient in operation and economical of manufacture.

15 A further object of the invention is to provide a coupling device which is especially adapted for use in connection with motor truck tractors and trailers.

20 Further objects of the invention will appear more fully hereinafter.

The invention consists substantially in the construction, combination, location and relative arrangement of parts, all as will be more fully hereinafter set forth, as shown in the 25 accompanying drawing, and finally pointed out in the appended claims.

Referring to the drawing:

Figure 1 is a view in side elevation of a 30 tractor and trailer employing a coupling mechanism embodying my invention.

Fig. 2 is a view in front elevation of a coupling mechanism.

Fig. 3 is a view in side elevation of the same.

35 Fig. 4 is a sectional view taken on the line A—B, Fig. 2.

Fig. 5 is a similar view taken on the line C—D, Fig. 2.

40 Fig. 6 is a similar view taken on the line E—F, Fig. 7.

Fig. 7 is a plan view of a modified structure embodying my invention.

Fig. 8 is a view in front elevation of the operating links employed in the modification shown in Fig. 7.

Fig. 9 is a side elevation of the construction shown in Fig. 7.

50 The same part is designated by the same reference numeral wherever it occurs throughout the several views.

In Figs. 1 to 5, inclusive, I have shown my invention as applied to a motor tractor and trailer, wherein I provide a member 10 pivotally mounted in bearings 11 which are 55 carried by the tractor. The member 10 is

provided with a chamber adapted to receive a plunger 12 therein. The plunger 12 is pivotally connected to swivel plate 16 by a pin 17, to which said plunger 12 is connected by pin 18 as shown. The plate 16 is carried by the trailer. A shock absorbing pad 21, may be placed in the bottom of the member 10 to receive the lower end of the plunger 12 as shown in Fig. 4.

60 Springs 19 are interposed between the plate 16 and member 10 to absorb or retard the shock or movement of the tractor and trailer relative to each other.

The main portion of the plunger 12 extends into the chamber of member 10, and 65 is provided with an annular groove 15. The member 10 has formed as a part thereof a casing 50 containing the spring 14 which normally presses a collar 51 forming part of a bolt rod 13, toward the hollow chamber 70 of member 10, thus pressing the ends of the rod 13 into the annular groove 15 of the plunger 12, and to retain the same in the chamber of member 10, but at the same time 75 allowing free swiveling movement of the plunger 12 therein. From this it will be seen that I have provided a coupling mechanism 80 which is exceedingly simple in structure, efficient in operation, and which may be cheaply manufactured, being made of but 85 a few standard parts.

The rod or bolt 13 may be operated in any desired manner. In Fig. 1 I show a simple arrangement where the coupling device is employed in connection with a motor 90 truck and trailer. T designates the motor truck and P the trailer. Pivotally mounted on the truck T is a bell crank lever Q, one arm of which is provided with a hook portion A, and the other arm of which is 95 loosely connected to bolt rod 13, by the connection R. The trailer P is provided with a pin or lug S, over which the hook A is adapted to fit. To join the tractor and trailer the tractor is backed up to the trailer, 100 the front end of the latter being held in sufficiently raised position, and in any suitable manner, such, for instance, as set forth in my Patent No. 1,179,793, issued April 18, 1916, thereby causing the plunger 12 to 105 clear the top of the member 10. The lever Q is then dropped so that the hook A engages the pin S, the arm R thereby withdrawing the bolt 13 and by starting forward the tractor, the lever Q draws the 110

trailer forward with it, thereby releasing the front end of the trailer from the support which maintains it raised, as explained in my said patent, and allows the plunger 12 to descend into the chamber of member 10. The lever Q then may be raised to allow the bolt 13 to engage the annular channel 15 of the plunger. To further facilitate the reception of the plunger 12 in the member 10, the end of the plunger may be beveled as shown best in Fig. 4, thereby insuring a proper insertion of the plunger in the chamber of member 10.

The withdrawal of the rod 13 from out of the hollow member 10 may also be accomplished from the operating end of the vehicle T in any desired or well known manner. I show a simple arrangement wherein a rod is connected to the member R and to a foot 26 pedal pivotally carried by the body of the vehicle T. It will be understood, however, that my invention, in its broad scope, as defined in the claims, is not to be limited or restricted in this respect.

In Figs. 6, 7, 8 and 9, I show a modified structure embodying my invention, and one which may be readily applied to trains or the like. In this arrangement the bearings 11 which support the member 10 are carried by one car and the plunger 12 is carried by the car to be coupled. I prefer to employ two bolts 13 operated simultaneously from a common point. To accomplish this I provide yokes 25, one for each bolt 13, engaging the same as shown. The yokes 25 are pivotally carried by brackets 26 secured to the bearings 11. The outer ends of the yoke members 25 are pivotally connected to the links 27, which links are likewise pivotally connected to each other by comparatively shorter links 28. The links 28 are secured to a handle R at their approximate middles. Thus it will be seen that when the handle R is turned in either direction, the links 28 are moved thereby pulling toward each other the links 27, and the yoke members 25, thereby withdrawing the bolts 13 from the annular channel 15 of the plunger 12.

Having now set forth the objects and nature of my invention, and having shown and described various embodiments thereof, what I claim as new and useful, and desire to secure by Letters Patent, is,—

1. In a coupling mechanism, the combination of a chambered member and an engaging member pivotally carried by the respective bodies to be coupled, said engaging member adapted to be received in the chamber of said chambered member, and means to retain said engaging member in its seat in the chambered member, and means for automatically detaching said engaging member from said chambered member.

2. In a coupling mechanism, the combina-

tion of a chambered member and an engaging member pivotally carried by the respective bodies to be coupled, said engaging member adapted to be received in the chamber of said chambered member, and means to retain said engaging member in its seat in the chambered member, and means to allow the swiveling movement of said engaging member relative to said chambered member, and means for automatically detaching said engaging member from said chambered member.

3. In a coupling mechanism, the combination with the bodies to be coupled, of a plunger pivotally carried by one of said bodies, a receptacle pivotally carried by the other of said bodies, and adapted to receive said plunger, and means for locking said plunger in said receptacle and means for automatically releasing said locking means.

4. In a coupling mechanism, the combination with the bodies to be coupled, of a plunger pivotally carried by one of said bodies, a receptacle pivotally carried by the other of said bodies, and adapted to receive said plunger, and means for locking said plunger in said receptacle and means for allowing free swiveling movement of said plunger in said receptacle, and means for automatically releasing said locking means.

5. In a coupling mechanism, the combination with the bodies to be coupled, of a plunger pivotally carried by one of said bodies, and provided with an annular groove, a receptacle pivotally carried by the other of said bodies, and adapted to receive said plunger, and automatically detachable means for engaging said groove to lock said plunger in said receptacle.

6. In a coupling mechanism, the combination with the bodies to be coupled, of a plunger pivotally carried by one of said bodies, and provided with an annular groove, a receptacle pivotally carried by the other of said bodies, and adapted to receive said plunger and a bolt adapted to project into said receptacle and into the groove of said plunger and means for automatically retracting said bolt out of said groove.

7. The combination with a tractor and trailer, of an engaging device carried by said trailer, a receptacle adapted to receive said engaging device, and carried by said tractor, means for connecting said tractor and trailer, and means operated by said connecting means for allowing said engaging device to be received by said receptacle.

8. The combination with a tractor and trailer, of an engaging device carried by said trailer, a receptacle adapted to receive said engaging device, and carried by said tractor, means for locking said engaging device in said receptacle to allow the free

swiveling movement thereof therein, means for connecting said tractor and trailer, and means operable by said connecting means for withdrawing said locking means.

5 9. The combination with a tractor and trailer, of a plunger carried by said trailer adapted to have free pivotal movement relative thereto, a receptacle carried by said tractor, and adapted to have free pivotal 10 movement relative thereto, and to receive said plunger therein, and means for yieldingly locking said plunger in said receptacle.

10 10. The combination with a tractor and trailer, of a plunger carried by said trailer 15 adapted to have free pivotal movement relative thereto, a receptacle carried by said tractor, and adapted to have free pivotal movement relative thereto, and to receive said plunger therein, and means for yield- 20 ingly locking said plunger in said receptacle to allow the free swiveling movement of said plunger in said receptacle.

11. The combination with a tractor and trailer, of a plunger carried by said trailer 25 adapted to have free pivotal movement relative thereto, and provided with an annular groove, a receptacle carried by said tractor and adapted to have free pivotal movement relative thereto, and to receive said plunger 30 therein, and a bolt adapted to yieldingly project into said receptacle and normally maintained in the groove of said plunger.

12. The combination with a tractor and trailer, of a plunger carried by said trailer, 35 a receptacle carried by said tractor to receive said plunger and afford a connecting means

between said tractor and trailer, and means for allowing swivel movement between said tractor and trailer about the vertical longitudinal and transverse axes of the point of 40 connection between said tractor and trailer and retractable means for locking said plunger in said receptacle.

13. The combination with a tractor and trailer, of a plunger carried by said trailer, 45 a receptacle carried by said tractor to receive said plunger and afford a connecting means between said tractor and trailer, and means for allowing swivel movement between said tractor and trailer about the vertical longitudinal and transverse axes of the point of 50 connection between said tractor and trailer, and springs positioned on opposite sides of said plunger and interposed between said tractor and trailer. 55

14. The combination with a tractor and trailer, of a plunger carried by said trailer, a receptacle carried by said tractor to receive said plunger and afford a connecting means between said tractor and trailer, and 60 means for allowing swivel movement between said tractor and trailer about the vertical longitudinal and transverse axes of the point of connection between said tractor and trailer, and springs carried by said tractor 65 and positioned on opposite sides of said plunger and interposed between said tractor and trailer at the point of connection there- 70 between.

In testimony whereof I have hereunto set my hand this 4th day of August, A. D. 1916.

WILLIAM BARBER.
